UNITED STATES PATENT OFFICE.

CLARENCE W. SPRAGUE, OF PHILADELPHIA, PENNSYLVANIA.

TENSION DEVICE FOR SHEARS.

No. 913,575.

Specification of Letters Patent.

Patented Feb. 23, 1909.

Application filed August 31, 1908. Serial No. 451,065.

To all whom it may concern:

Be it known that I, CLARENCE W. SPRAGUE, a citizen of the United States, residing at Philadelphia, in the county of Philadelphia and State of Pennsylvania, have invented 5 certain new and useful Improvements in Tension Devices for Shears, of which the following is a specification, reference being had therein to the accompanying drawing.

10 My invention relates to improvements in tension devices for shears.

The object of my invention is to provide a tension device for shears in which an even tension may be maintained between the two 15 cutting blades and at the same time doing away with the usual harshness in ordinary tension devices now in use.

Another object of my invention is to provide a simple, cheap and effective tension 20 device which can be readily attached to any form of shears now in use, and in which the parts can be readily replaced when they become worn.

In the accompanying drawings, Figure 1, 25 is a side elevation of a pair of shears showing my tension device applied thereto. Fig. 2, is a vertical, longitudinal, sectional view of Fig. 1. Fig. 3, is a detached, perspective view of the several parts forming my tension 30 device, and which may be applied to any form of shears. Fig. 4, is a sectional view of a modification. Fig. 5, is a detached, perspective view of the cup and washers shown in the modification.

35 Referring now to the drawings, 1 represents one blade of a pair of shears, and 2 the other blade which are pivoted together in the usual manner by the pivot 3, all of which is of the ordinary form of shears and 40 is simply shown to show the application of applicant's tension device to the ordinary shears.

The blade 1 adjacent the pivot 3, and in rear thereof, is provided with an opening 4 extending therethrough, and which could be made during the manufacture of the shears. This opening could be drilled in the completed blade, thus making the device applicable to any ordinary shears. As before 50 stated, the opening 4 is adjacent the pivot 3 so that the blade 2 when swinging on the pivot will at all times cover or partially cover the inner end of the opening in order to retain the friction disks therein, and thus 55 requiring no retaining means, making the

device more simple and reducing the cost, and also making the removal of the operative parts more simple, by the mere removal of the blade 2. The opening 4 has its inner 60 end larger as indicated at 5, and fitting within the said opening is a sleeve 6 which is of a length considerably greater than the thickness of the blade. The inner sleeve is provided with the laterally extending flange 7 which rests within the enlarged portion 5 65 of the opening, and the inner end of the sleeve or bushing is flush with the inner edge 8 of the blade 1, so that the same will not interfere with the movement of the blades upon each other.

70 The sleeve or bushing 6 has at its inner end an enlarged opening 9 ending in the upper smaller opening 10 which is internally screw-threaded. Extending through threaded opening 10 is a thumb-screw 11 having 75 the enlarged head 12 by means of which the screw can be readily moved in or out, as desired. Within the said enlarged opening is a washer 12 which is made of any desired metal, and against which the inner end of 80 the screw 11 is adapted to bear. Within said enlarged opening below the washer 12, is a second washer 13 composed of rubber or other elastic material, and below this elastic washer is still another metal washer 14, the 85 lower face of which is slightly convexed and ground smooth to allow it to freely pass over the upper face 15 of the lower blade 2.

90 The set screw bearing upon the washer 12 and the elastic washer 13 being between said washer and the washer 14, it will be seen that the washer 14 does not have a positive unyielding contact with the lower blades as those now in use, and the superposed elastic washer prevents the thumb-screw 95 from being worked loose by the movement of the blade against the disk 14 like those in which the set screw directly engages the friction disk. This produces a more effective tension device, and also provides a device 100 which is wholly carried by the sleeve or bushing, and which forms a more effective device. The sleeve 6 may be, if desired, welded in the opening which forms a more perfect and even inner face when ground 105 down smooth with the lower face of the blade 1, although it can be simply applied as shown and a set screw holding it, owing to the pressure thereon through the washers. The set screw being in rear of the pivot, it 110

will be seen by screwing the same downwardly the outer cutter edges will be brought together.

In Figs. 4 and 5, instead of using a washer 5 14, I use a cup-shaped member 14' which is of a depth slightly greater than the washers 12' and 13, and in which said washers loosely fit. The cup-shaped member is of a diameter slightly less than the opening 9, so that 10 there will be no possibility of any binding thereof within the opening. This cup-shaped member not only provides a carrying means for the washers 12' and 13, but also has the advantage over the washer 14 of 15 preventing the same from accidentally slipping out of the opening 9 should the screw 3 work loose, which might possibly be the case with the washer 14. The cup-shaped member has all other advantages of the 20 washer 14.

Having thus described my invention, what I claim, and desire to secure by Letters Patent, is:—

1. The combination with a pair of shears, 25 of a set screw extending through one blade of the shears, a washer against which said set screw bears, an elastic washer below the first mentioned washer, and a third washer below the elastic washer and adapted to 30 bear against the upper face of the other blade.

2. The combination with a pair of shears, 35 of a bushing set within one blade and flush with the lower face thereof, of a set screw within said bushing, a metal washer within the bushing and against which the set screw bears, an elastic washer below said metal washer, and a metal washer below the elastic washer and bearing against the upper 40 face of the other blade of the shears.

3. The combination with a pair of shears, 45 of a bushing set within one blade and flush with the inner face thereof, said bushing having contracted outer end, a set screw screwed into said contracted outer end, a washer within said bushing and against which the set screw bears, an elastic washer within the bushing below the first-mentioned washer, and a washer below the elastic 50 washer and adapted to engage the inner face of the other blade of the shears.

4. The combination with a pair of shears, 55 one blade having an opening therethrough on the inside of the pivot, said blade having its inner face provided with an annular re-

cess surrounding said opening, a bushing within the opening and having a flange resting in the annular recess to prevent the outward movement of the bushing, said bushing having its flange flush with the inner face of the blade and its outer end extending a distance beyond the outer face of the blade, a set screw screwed through the outer extended end, said bushing having an enlarged bore at its inner end, a metal washer 60 within the bushing and against which the set screw bears, an elastic washer below the metal washer, and a second metal washer below the elastic washer and its lower face slightly convexed which is adapted to bear 70 upon the inner face of the other blade, said bushing being so positioned that the other blade at all times covers the same and retains the washer therein.

5. The combination with a pair of shears, 75 of a set screw extending through one blade of the shears, a cup-shaped member loosely mounted in the blade below the set screw and adapted to engage the upper face of the other blade, an elastic member within the 80 cup-shaped member, a washer within the cup-shaped member and bearing against the elastic member, and against which the set screw is adapted to bear.

6. The combination with a pair of shears, 85 one blade having an opening therethrough on the inside of the pivot, said blade having its inner face provided with an annular recess surrounding the said opening, a bushing within said opening and having a flange 90 resting in said annular recess, to prevent the outward movement of the bushing, said bushing having its flange flush with the inner face of the blade and its outer end extending a distance beyond the outer face of 95 the blade, a set screw screwed through the outer embedded end, a cup-shaped member loosely mounted in the lower end of the bushing and having its closed end bearing against the inner face of the other blade, a 100 flexible member within the lower end of the cup-shaped member, and a metal washer within the cup-shaped member and against which the set screw bears.

In testimony whereof I affix my signature 105 in presence of two witnesses.

CLARENCE W. SPRAGUE.
